UNITED STATES PATENT OFFICE.

WILLIAM T. MERSEREAU, OF ORANGE, NEW JERSEY.

DESIGN FOR A RECEPTACLE FOR BUSINESS-CARDS.

SPECIFICATION forming part of Design No. 12,334, dated June 28, 1881.

Application filed May 11, 1881. Term of patent 3½ years.

To all whom it may concern:

Be it known that I, WILLIAM T. MERSEREAU, of Orange, Essex county, New Jersey, have invented and produced a new Design for a Receptacle for Business-Cards, of which the following is a specification, reference being had to the accompanying drawings, and to the letters of reference marked thereon, in which—

Figure 1 is a view of the receptacle folded; Fig. 2, a side view of the same opened, Fig. 3 an end view of the same opened.

In the drawings like parts of the invention are pointed out by the same letters of reference.

The nature of the design is clearly shown in the drawings; and it consists of a bedstead-shaped receptacle for business-cards, the head-piece A and foot-piece B of which are folded

down upon the card inserted and resting upon the side rails, C, of the bedstead. 20

In the drawings, A shows the head-piece, provided with the openings a; B, the foot-piece, provided with the openings b; and C are the side rails, provided with ears c. The upper portions of the head-piece A and foot-piece B 25 are curved, as shown at a² b², and gradually rise centrally.

Having now described my design, what I claim as new is—

The design for a receptacle for business-30 cards, as shown and described.

WILLIAM T. MERSEREAU.

In presence of—

W. E. HEINEMAN,

WILLIAM V. H. HICKS.
